UNITED STATES PATENT OFFICE.

FRANK W. GAULT, JR., OF OKOLONA, KENTUCKY, ASSIGNOR TO THE PERFECT COMBUSTION BURNER AND MIXER COMPANY, OF DOVER, DELAWARE, A CORPORATION OF DELAWARE.

GAS-BURNER.

1,325,782.

Specification of Letters Patent. Patented Dec. 23, 1919.

Application filed February 17, 1919. Serial No. 277,634.

To all whom it may concern:

Be it known that I, FRANK W. GAULT, Jr., a citizen of the United States, residing at Okolona, in the county of Jefferson and 5 State of Kentucky, have invented a new and useful Gas-Burner, of which the following is a specification.

This invention relates to gas burners.

Gas, both artificial and natural is widely 10 used, in industrial plants on account of its adaptability to conditions and its susceptibility to regulation.

An object of this invention is to provide 15 a burner wherewith gas may be burned so as to produce a low flame of wide area, simulating the appearance and effect of a bed of glowing coke.

Another object is to provide a burner, 20 which when used in connection with the air and gas mixer, described and claimed in Patent #1,286,582, granted to applicant December 3, 1918, will produce conditions that have long been sought in certain arts, such as candy making, wherein it is essential that 25 the heat be evenly distributed over a wide area of the bottom of a receptacle, such as a kettle.

With the foregoing and other objects in view, the invention consists of the novel construction and arrangement of parts illustrated in the accompanying drawing, which forms a part of this specification, wherein is set forth an embodiment of the invention, but it is to be understood that such changes 30 and modifications may be resorted to as come within the scope of the claims appended hereunto.

In the drawing, wherein similar reference characters designate like parts in the 40 several views, Figure 1, is a perspective view of an embodiment of the invention: Fig. 2, a plan view: Fig. 3, a central longitudinal section: Fig. 4, a section on line 4-4 of Fig. 2: Fig. 5, a detached detail showing the 45 method of adjusting the burner plate: Fig. 6, an elevation of the adjusting screw and Fig. 7, a view showing a method of using the burner.

The burner designated as an entirety by 50 the reference numeral —10—, comprises a body —11— formed preferably as an integral casting consisting of a bottom and vertical side walls, it is made massive to resist

the action of heat, and is cast in sand, in order that the surface may be rough. A 55 ledge —12— extends around the inside, a spaced distance from the bottom, a burner plate —13— disposed upon the ledge divides the interior into two portions, a lower or distribution chamber —14— and an upper, 60 or combustion chamber —15—. The body is provided in its lower portion with a screw threaded aperture —16— which opens into the distribution chamber and is adapted for the reception of a supply pipe —17—. The 65 roughness of the surface of the body is such that the burner plate does not lie close on the ledge, nor do its edges lie close against the walls, consequently gas will pass around the edge of the plate and being ignited will 70 form what I term a lazy flame. A plurality of slits, —18, 19— arranged in two groups, extend inward from the opposite edges of the plate in alternate parallel relationship, to within a spaced distance of the opposite edge. 75 The slits are very narrow and open into the space between the edge of the plate and the wall, and gas which passes through them is lighted by the lazy flame. When used in connection with my mixer, as previously 80 mentioned, there is considerable pressure exerted on the underside of the burner plate, and means must be provided for holding it in position. For so holding the plate and adjusting it to and from the ledge, I have 85 provided a screw having a head —20— a neck —21— and a threaded body portion —22—. The plate is provided near each corner with a marginal recess —23—, extended in from the edge thereof, which is adapted 90 to receive the neck of a screw. To place the plate in the burner, the necks of the screws are placed in the recess, the screws hanging pendent therefrom, the plate is then lowered 95 into the burner and the screws engaged in screw threaded holes —24— in the ledge, the screws are then turned by means of a screw driver to draw the plate down to the desired position where it will be securely held, the head of the screws preventing it from 100 being blown out by the air pressure and the shoulder holding it spaced from the ledge.

I have observed that with gas at a normal pressure of about 5 ounces and with a low air pressure, a high flame is produced, but 105 as the air pressure is increased the flame is

reduced until at a pressure of 25 pounds or upward, a low blue flame is formed which I term a blanket flame.

In Fig. 7, the burner is shown as supported by a stand —25—, beneath a kettle —26—, the kettle being upheld by a stand —27—.

Having thus described my invention so that others skilled in the art pertaining thereto can make and use the same,

I claim:

1. A burner comprising a body having vertical walls, a ledge extending inward from the sides of said walls a spaced distance from the bottom thereof, a burner plate having a plurality of slits extended inward from the edges thereof, said plate being supported by said ledge, and means for introducing gas into the space below the plate.

2. In a burner as characterized, a body comprising a bottom and integral vertical side walls, a supporting ledge extending around the inner side of said wall a spaced distance above said bottom, and a burner plate resting on said ledge, dividing the interior into distribution and combustion chambers, the edges of said plate being a

spaced distance from the walls, the body having an opening in the lower portion thereof for the reception of a feed pipe.

3. In a burner as characterized, a body comprising a bottom and integral vertical side walls, a supporting ledge extending around the inner side of said walls a spaced distance above said bottom, a burner plate resting on said ledge dividing the interior into distribution and combustion chambers, said plate being provided with a plurality of slits extended inward from opposite sides thereof in alternate parallel relationship, and adjusting screws mounted in said ledge, each of said screws comprising a head, a neck and a body portion, the plate having marginal recesses for the reception of the necks of said screws.

4. A burner comprising a body having vertical walls, a burner plate provided with a plurality of perforations supported within said body, a spaced distance below the top thereof, and a plurality of adjusting screws each comprising a body, a neck and a head, the plate having marginal recesses for the reception of the necks of said screws.

FRANK W. GAULT, JR.
